James G. Gordon. Scaglische. New York.
Letters Patent (Design No. 155) dated Oct. 2, 1847.

The schedule referred to in these Letters Patent and making part of the same.

To all whom it may concern: Be it known that I James G. Gordon of Scaglische in the County of Rensselaer and State of New York, have invented or produced a new and useful ornamental design for an air tight Cooking Stove, and I do hereby declare that the accompanying drawings are full and accurate delineations of a stove after my said design, Fig. 1. being, a perspective view to shew the general form, and Fig. 2. a side view upon a larger scale to shew the detail of ornament. Fig. 3. represents the front and Fig. 4. the back of the stove. Fig. 5. is a section of the door mouldings.

What I claim as my invention and desire to secure by Letters Patent is, the combination and arrangement of ornamental forms and figures shewn in the accompanying drawings and forming an ornamental design for an air tight Cooking Stove.
